DESK CALENDAR OR SIMILAR ARTICLE

Henry Steiner, Hong Kong, assignor to The Dow Chemical Company, Midland, Mich.

Filed June 27, 1972, Ser. No. 266,689

Term of patent 14 years

Int. Cl. D19—03

U.S. Cl. D19—20

Fig. 1

Fig. 2

FIG. 1 is an isometric view of a desk calendar or similar article, showing my new design; and

FIG. 2 is an end elevational view.

The characteristic features of my design reside in a desk calendar or similar article comprising a rhombohedron body having opposing end surfaces substantially perpendicularly disposed to four equilateral side surfaces, each of said side surfaces including permanently affixed indicia of three sequential months of a year, the days of the week and the current dates of said year.

I claim:

The ornamental design for a desk calendar or similar article, as shown and described.
